SELF-SERVER DISPLAY CABINET

Domenico Patriarca, Cranston, R. I.

Application November 16, 1951, Serial No. 256,785

4 Claims. (Cl. 312—31)

The present invention relates to the construction of display cabinets, and has particular reference to a novel arrangement for a self-server cigar dispensing cabinet.

The principal object of the invention is to provide a self-server cigar display cabinet which gives prospective purchasers an unobstructed view of the cigars on display within the cabinet.

Another object of the invention is to provide means for keeping the cigars displayed within the case in an atmosphere of constant prescribed humidity.

An additional object of the invention is to provide a narrow frame around the front of the display cabinet.

A further object of the invention is to provide the narrow frame with a non-metallic top rail having a metal T beam which receives sliding plate glass panels and also functions as a reinforcing cross beam.

Still another object of the invention is to provide a self-server display cabinet which is constructed to seal the front display portion when the glass panels are closed.

A further object of the invention is to provide a special handle for the plate glass panels for facilitating opening and closing of the panels and for insuring sealing of the display case to maintain a constant humidifying atmosphere.

An additional object of the invention is to provide the end rail of the narrow frame with resilient strips to insure sealing of the self-server display cabinet when the plate glass panels are in a closed position.

With the above and other objects and advantageous features in view, the invention consists of novel features of construction and novel combinations of parts more fully disclosed in the detailed description following, in conjunction with the accompanying drawings, and more specifically defined in the claims appended thereto.

In the drawings,

Fig. 1 is a perspective view of an illustrative display cabinet, showing the front thereof;

Fig. 2 is a perspective view of the rear of the display cabinet, the doors being open to disclose the humidifying unit;

Fig. 3 is a cross section on the line 3—3 of Fig. 1;

Fig. 4 is a cross section on the line 4—4 of Fig. 1;

Fig. 5 is a cross section on the line 5—5 of Fig. 1; and

Fig. 6 is a perspective view of a modified form of metal handle for the plate glass panels.

It has been found desirable to provide a special construction for a display case for cigars and the like, which maintains the cigars in proper condition for smoking, which is so arranged that the cigars are attractively displayed, and which is so designed that a purchaser can serve himself after being attracted by the display.

To this end, I provide a cabinet which is substantially completely open to view from the front, and which has a series of ladder step shelves so positioned that a large number of boxes of cigars are attractively displayed in rearwardly ascending relation. The rear of the cabinet is hollow for storing additional boxes of cigars and for

2

housing a humidifying unit which is set to maintain a desired humidity in the cabinet, the rear being accessible through sliding doors or the like.

The cabinet front includes a narrow frame, preferably made of wood, which has a lower rail with ball bearing slide grooves for supporting glass slide panels, an upper rail which is strengthened to provide upper grooves for the panels although reduced in height to accommodate a top panel, and side rails which are recessed to seat the glass panel ends, and are provided with resilient sealing strips whereby the interior of the cabinet is readily kept humidified as hereinafter explained.

Since the purpose of the construction is to permit a purchaser to serve himself, the glass panels are equipped with special handle bars of narrow width, which do not protrude into the display space and are so positioned that they may be grasped for opening movement at any point along the entire length of the panel, the bars cooperating with the sealing strips and distributing the opening and closing pressures along the entire panel length.

Referring to the drawings, the self-server cigar display cabinet 10 includes a front display section 11 and a rear storage section 12 separated from the front section by a step back perforated ladder partition screen 13. The rear storage section 12 has a humidifying unit 14 which is regulated in standard manner to create a prescribed desirable humid atmosphere within the display case, the perforated partition allowing free circulation of this humidified atmosphere between the front display section and the rear storage section. Access to the rear storage section is gained through the back 15, which has movable sliding doors 16 and 17. Access to the front storage section is gained through the front 18 which has movable sliding panels 19 and 19a made of plate glass or other transparent material. The display section front includes a frame 20 having a top rail 21, a bottom rail 22, and two side rails 23 and 24, the rails being of special construction as explained below.

The top rail 21 is of narrow construction in order to provide a clear unobstructed view into the display section of the cabinet. It has a longitudinal T-shaped slot 25 as shown in Fig. 3 having an upper portion 26 and a wide lower portion 27. A T-shaped metal reinforcing beam 28 is slidably mounted within the slot 25 to reinforce the non-metallic rail 21 the depending portion 29 of the beam 28 forming adjacent smooth unobstructed runways 30 and 31 with the sides of the lower slot portion 27, in which the plate glass panels 19 and 19a slidably move. The bottom rail 22 has a longitudinal slot 32 as shown in Fig. 4 which has a central longitudinal strip 33 forming adjacent runways 34 and 35 in which the plate glass panels are slidably movable on ball bearing strips 36 positioned in the runways 34, 35. The sealing ends 37 and 38 of the plate glass panels 19 and 19a each have a metal hand bar 39 which is shaped as shown in Fig. 5 to encase the end of the plate glass panel, including a forward U-shaped portion 40 which seats over and is cemented to the end of the plate glass panel. The metal hand bar 39 extends for the length of the plate glass panel, and has a finger grasping portion 41 which is upstanding as shown in Fig. 5, or which may be of arcuate form as shown at 42 in Fig. 6. The side rails 23 and 24 each have a longitudinal U slot 43 in which a strip of resilient material 44 is fastened or secured; see Fig. 5, the strip extending the length of the rail. The resilient strips 44 cooperate with the U-shaped portions at the ends of the plate glass panels to seal the opening when the panels are in a closed position.

It is now clear that applicant's construction provides a self-server display cabinet which has an unobstructed view of the display cigars and the like, and operates to seal within the display cabinet an atmosphere which has

a constant prescribed desirable humidity. The metal reinforcing T beam mounted within the non-metal top rail makes possible a narrow frame for the glass plate panels and completely eliminates the employment of screws, bolts or other securing means within the top rail. This construction provides adjacent top rail runways which are smooth and without obstruction. The metal reinforcing T beam also keeps the frame in continuous alignment so that the panels slide freely within their runways and close tightly against the sealing strips of the side rails. The metal construction of the handles makes possible easier gripping to move the plate glass panels and also functions to seat the panels snugly against the resilient side strips whereby sealing of the humidified atmosphere is further insured. The whole construction thus provides a self-server combination which has a substantial completely open front framed by narrow rails rigidly held in place, the panels being readily opened by pressing anywhere along the hand bar, the parts cooperating to preserve the humidified atmosphere.

Although I have described a specific constructional embodiment of my invention using a wood frame and metal handle bars for the glass panels, it is clear that plastic having the requisite strength may be used for the cabinet parts, and that changes in the size, shape, arrangement and material of the parts may be made to suit different display requirements, without departing from the spirit and the scope of the invention as defined in the appended claims.

I claim:

1. In a display and sales store cabinet for self-service, the cabinet having a base, side walls, a rear wall, a top, a lower front wall, and an upper front opening inclined forwardly from the top to the lower front wall, a frame around the upper front opening including a top rail, a bottom rail, and side rails, the top rail having a longitudinal T-shaped slot, a T-shaped metal beam in said slot having a depending portion intermediate the sides of the vertical portion of the T-shaped slot, the cross bar of the T-shaped beam resting in and being supported by the cross bar portion of the T slot and providing front and rear spaced runways therewith, the bottom rail having a longitudinal slot, a central longitudinal strip in said bottom rail slot spaced from the sides thereof and providing spaced runways therewith, ball races in said bottom rail front and rear runways, said side rails having longitudinal slots adapted to seat receive the sides of the panels, and transparent panels respectively mounted in the front and the rear top and bottom rail runways.

2. In a display and sales store cabinet for self-service, the cabinet having a base, side walls, a rear wall, a top, a lower front wall, and an upper front opening inclined forwardly from the top to the lower front wall, a frame around the upper front opening including a top rail, a bottom rail, and side rails, the top rail having a longitudinal T-shaped slot, a T-shaped metal beam in said slot having a depending portion intermediate the sides of the vertical portion of the T-shaped slot, the cross bar

of the T-shaped beam resting in and being supported by the cross bar portion of the T slot and providing front and rear spaced runways therewith, the bottom rail having a longitudinal slot, a central longitudinal strip in said bottom rail slot spaced from the sides thereof and providing spaced runways therewith, ball races in said bottom rail front and rear runways, said side rails having longitudinal slots adapted to seat receive the sides of the panels and transparent panels respectively mounted in the front and the rear top and bottom rail runways, each panel having a metal handle mounted on its outer end, each handle being substantially the height of the panel.

3. A display and sales cabinet for cigars, including a base, side walls, a rear wall, a top, a lower front wall and an upper front opening, said upper front opening inclining forwardly from the top to the lower front wall and said lower front wall inclining rearwardly from the upper front opening, said upper front opening having a top rail, a bottom rail, and side rails, the top and bottom rails having longitudinal front and rear spaced runways, and the side rails having longitudinal grooves provided with sealing strips, transparent panels slidably mounted in said runways and adapted to seal seat in said side rail grooves, a step back perforated step partition in said cabinet extending rearwardly and upwardly from the top of the lower front wall to the top of the rear wall, a humidifier positioned behind the perforated step partition, means for mounting said humidifier in elevated relation with respect to said base whereby to afford better circulation of the humidified atmosphere through the step partition.

4. A display and sales cabinet as set forth in claim 3 further characterized in that the rear wall has an upper portion comprising the rear step of the partition and a lower portion comprising a slidable closure for permitting access to the humidifier.
